FRED J. HEIDEMAN, OF DETROIT, MICHIGAN, ASSIGNOR TO KELVINATOR CORPORATION, OF WILMINGTON, DELAWARE, A CORPORATION OF DELAWARE.

COMPRESSOR FOR REFRIGERATING APPARATUS.

1,273,366.

Specification of Letters Patent. Patented July 23, 1918.

Application filed January 14, 1918. Serial No. 211,750.

To all whom it may concern:

Be it known that I, FRED J. HEIDEMAN, a citizen of the United States, residing at Detroit, in the county of Wayne and State 5 of Michigan, have invented a certain new and useful Improvement in Compressors for Refrigerating Apparatus, of which the following is a full, clear, and exact description, reference being had to the accompanying 10 drawings.

This invention relates to refrigerating machinery and especially to the construction of a compressor employed in such machinery.

Among the objects of the invention are the 15 provision of a cheap, simple and efficient valve construction for small sized compressors; the provision of a valve and valve body of such construction as to shield from the corrosive action of the refrigerant the 20 base metal of which the compressor is chiefly constructed; the provision of a device which will be rigidly held in place when assembled, instantly taken apart when the compressor is disassembled, and in which grinding and 25 adjustment to the valves is greatly facilitated; while further advantages of the invention will become apparent as the description proceeds.

In the drawings accompanying and forming 30 a part of this application I have shown one embodiment of my said invention, although it will be understood that these drawings are illustrative merely and are not to be given any limiting effect. In these 35 drawings Figure 1 is a sectional view through a part of a two-cylinder compressor constructed in accordance with my invention; Fig. 2 is a transverse sectional view on the line 2--2 of Fig. 1; and Fig. 3 is 40 a separated perspective view of the different valve and closure parts.

Describing the parts by reference characters:—1 represents the cylinder block of the compressor which is preferably of cast iron 45 and is here shown as provided with two parallel cylindrical bores 2--2, although the number may be increased or diminished. Each of these bores is lined with a cylindrical sleeve 3 of non-corrodible metal such 50 as bronze, the upper end of each sleeve being preferably provided with an external annular flange 4 snugly received in a rabbet formed in the cylindrical block. The upper face of each flange may also be formed with 55 an annular groove 5, for obstructing leakage,

although these minor features are not necessary to the use of my invention.

Superposed on top of the cylinder block 1 is a head member 6, also preferably formed of cast iron, and formed in alignment with each cylinder with an aperture 7 of smaller diameter than the sleeve 3. Located in each aperture is the cylindrical portion 8 of a valve body whose lower end is formed with a laterally projecting circular flange 9 seated 60 flush in a recess in the head member concentric with the aperture 7. This flange is of sufficient width to overlap the sleeve 3 of the cylinder to which it is applied and the entire valve body is constructed of some 65 metal which is at once resistant to the corrosive effect of the refrigerant fluid and of sufficient hardness to withstand the hammering of the valves. For use with a sulfur dioxide refrigerant I preferably employ a 70 hard bronze which is high in copper and alloyed chiefly with tin, though I do not restrict myself to this composition or even 75 to these ingredients.

Other alloys may sometimes be necessary, 80 although this substance appears to operate successfully with most of the fluids now in practical use.

Each valve body is traversed by a hollow chamber, formed at the flanged end with a 85 valve seat 10 of smaller diameter than the chamber communicating with the cylinder by an aperture 11. The opposite end of the chamber is formed with a spider-seat 12, such as an internal rabbet of appropriate depth, 90 and receiving the arms 13 of a spider whose body is formed with an elongated cylindrical boss 14 projecting toward the valve seat. This boss is bored for the reception of the 95 valve stem 15 whose head 16 is located between the boss and valve seat so as to have a limited range of movement. The lower end of this boss is counterbored as shown at 17 to prevent the hammering of the valve from upsetting the metal and pinching the valve 100 stem.

The thickness of the spider is such as to bring its upper surface substantially flush with the upper surface of the head member 6 so as to permit the spider to be held in 105 place by engagement with the cover plate 20 which is clamped upon the top of the head by means of screws 21—21 arranged in any suitable number and preferably traversing the head and tapped into the cylinder block, 110

The lower face of the cover plate is formed with a channel 22 whose width is less than the diameter of the spider so that the latter will be engaged and held in place by the instrumentality of the cover plate. Surrounding each boss is a spiral spring 25 by means of which the valve is yieldingly depressed, its lower end being received in a groove 26 formed in the valve head. The upper end 10 of each valve stem preferably projects above the top of its spider and is squared as at 27 or otherwise formed to receive a suitable tool whereby the valve may be ground to its seat when necessary. The upper face of the 15 top plate is formed with a flattened seat 30 for the reception of an outlet fitting (not shown) which communicates with the channel 22 by means of the passageway 31.

By the arrangement illustrated and described the entire cylinder is incased in non-corrodible metal so that no grit, scale, or oxid from the iron can become dislodged under the corrosive action of the refrigerant to fall into the cylinder and cause an abrasion of its walls; the valve is likewise shielded from the corrosive effects of the refrigerant since the valve body, spider, and spring are also preferably made of the same resisting material; the clamping of the 25 cover to the head and the head to the cylinder block, holds the spiders in their seats, the valve bodies in their apertures, and the cylinder sleeves in their bores, while permitting their easy release; the movement of the 30 valves is limited so that quick action is secured; while cheap and rapid manufacture is possible.

It will be understood that many changes in construction and detail may be made 40 within the scope of my invention as defined in the claims hereto annexed.

Having thus described my invention what I claim is:—

1. In a compressor for refrigerating machinery, the combination with a cast-iron cylinder block having a cylinder-bore and a head member having an aperture smaller than said bore and registering therewith, of a non-corrodible metal sleeve mounted in 45 said bore, a hollow body also of non-corrodible metal inserted in said aperture and having a flange overlapping said sleeve at all points, and a non-corrodible valve member in said hollow body.
- 55 2. In a compressor for refrigerating machinery, the combination with a cast-iron cylinder block having a cylinder-bore and a head member having an aperture smaller than said bore and registering therewith, of a non-corrodible metal sleeve mounted in 60 said bore, a hollow body of non-corrodible metal traversing said aperture and substantially flush with the surface of said head member at each end, the end of said body 65 next to said cylinder having a lateral flange

of greater diameter than said metal sleeve, and a valve in said body.

3. In a compressor for refrigerating machinery, the combination of a cast iron cylinder block having a faced end and a bore 70 opening through said end, said bore being surrounded by a rabbet, a cast-iron head member detachably secured to said faced end, and having an aperture smaller than said bore and in alignment therewith, said aperture also surrounded at the end next the cylinder bore by a rabbet of approximately the same diameter as the cylinder bore, of a non-corrodible metal sleeve in said bore and in said head, each sleeve having a 75 flange fitting its own rabbet and engaging the opposite flange, whereby each is secured in place.

4. In a compressor for refrigerating machinery, the combination with a cylinder 85 block having an open ended bore, of a closure member having a bore therethrough, said bore being rabbeted at the end away from the cylinder and being formed with a valve seat at the end next said cylinder, a 90 spider having its arms seated in said rabbet and having an apertured body, a valve having its stem slidably supported by said body and its head cooperating with said seat, and a top plate secured to the outer face of said 95 closure and having a passageway registering with said bore, the sides of said passageway overhanging said spider whereby the latter is secured in place.

5. In a compressor for refrigerating machinery, a cylinder head closure traversed by a longitudinal bore formed with a valve seat at its inner end and a rabbet at its outer end, a spider having arms seated in said rabbet and a longitudinally bored body, a 100 valve having its stem slidably received in said spider bore and its head cooperating with said seat, the end of said stem projecting beyond said spider and formed for the reception of a tool whereby it may be rotated, and a cover plate clamped to said closure and engaging said spider, said cover plate having a passageway communicating with said first bore and receiving the end 105 of said stem.

6. In a compressor for refrigerating machinery, a cylinder head closure traversed by a longitudinal bore formed with a valve seat at its inner end and a spider seat at its 110 outer end, a spider in said spider seat and having a longitudinally bored body depending toward said valve seat, a puppet valve having its stem projecting into the spider-bore and its head located between said spider-body and valve seat, the longitudinal 115 play of said valve head being very small, a spring carried by said spider and yieldingly holding said valve head to its seat, and means securing said spider in its seat.

7. In a compressor for refrigerating ma- 120

chinery, a cylinder head closure traversed by a longitudinal bore formed with a valve seat at its inner end and a spider seat at its outer end, a spider in said spider seat and having a longitudinally bored body depending toward said valve seat, a puppet valve having its stem projecting into the spider-bore and its head located between said spider-body and valve-seat, a helical 10 spring embracing said spider-body and engaging the adjacent face of the valve-head, and means securing said spider in its seat.

8. In a compressor for refrigerating machinery, a cast-iron cylinder block having 15 a plurality of open cylindrical bores therein, each rabbeted at its open end, a non-corrodible metal sleeve in each bore having a flange seated in the corresponding rabbet, a cast iron head member having in alinement 20 with each sleeve a bore smaller than the sleeve and a rabbet overlapping the edge of such sleeve, a non-corrodible metal valve-body located in each of said last bores and

having a flange seated in the corresponding rabbet and engaging the sleeve opposite thereto, each of said bodies having a longitudinal chamber formed with a valve seat at the cylinder end and a spider seat at its opposite end, a spider in each spider seat, a valve coöperating with each valve seat and guided by the corresponding spider body, the end of the valve stem projecting beyond said head member, a spring interposed between each spider and its valve, a cover plate superposed upon said head member 35 and engaging all said spiders, said plate having a channel communicating with all said valve chambers and receiving the projecting valve-stems, and means securing said cover plate, head member, and cylinder 40 block together whereby said sleeves, valve bodies, and spiders are held in place.

In testimony whereof, I hereunto affix my signature.

FRED J. HEIDEMAN.
